UNITED STATES PATENT OFFICE

115,832

DESIGN FOR A WINDOW SHELF

Roderick M. Koch, Evansville, Ind.

Application December 28, 1938, Serial No. 82,013

Term of patent 7 years

To all whom it may concern:

Be it known that I, Roderick M. Koch, a citizen of the United States, residing at Evansville, in the county of Vanderburg and State of Indiana, have invented a new, original, and ornamental Design for a Window Shelf, of which the following is a specification, reference being had to the accompanying drawing, forming part thereof.

I claim—

The ornamental design for a window shelf, as shown.

RODERICK M. KOCH.
